[57] CLAIM

The ornamental design for a ball point pen desk set, as shown and described.

DESCRIPTION

FIG. 1 is a front elevational view of a ball point pen desk set showing my new design, all other sides being identical thereto;

FIG. 2 is a front elevational view of the ball point pen with the base member removed for convenience of illustration, all other sides being identical thereto;

FIG. 3 is a front elevational view of the base member with the ball point pen removed for convenience of illustration, all other sides being identical thereto;

FIG. 4 is a top plan view of FIG. 3; and,

FIG. 5 is a bottom plan view of FIG. 3.

FIG. 1

FIG. 2

FIG. 3
